Primary Examiner — Robert M Spear*Assistant Examiner* — Rhea Shields(74) *Attorney, Agent, or Firm* — Larson & Larson, P.A.; Frank Liebenow; Justin P. Miller(57) **CLAIM**

We claim the ornamental design for an intramedullary tang actuator, as shown and described.

DESCRIPTION

FIG. 1 is an isometric view of the intramedullary tang actuator showing my new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof; and,

FIG. 8 is a cross-sectional view thereof.
